UNITED STATES PATENT OFFICE.

EMIL A. ANDERSON, OF SWEA CITY, IOWA.

CLEANER FOR EXCAVATING-DIPPERS.

1,128,215.

Specification of Letters Patent.

Patented Feb. 9, 1915.

Application filed June 13, 1913. Serial No. 773,441.

To all whom it may concern:

Be it known that I, EMIL A. ANDERSON, citizen of the United States, resident of Swea City, county of Kossuth, State of Iowa, have invented certain new and useful Improvements in Cleaners for Excavating-Dippers, of which the following is a specification.

The object of my invention is to provide a means for scraping the inside of an excavating dipper to prevent the contents thereof from sticking or delaying the discharge of the dipper load and the operation of the machine.

A further object is to provide a cleaning device which will be positive and reliable in its action and of simple, economical construction.

The invention consists generally in various constructions and combinations, all as hereinafter described and particularly pointed out in the claims.

In the accompanying drawings forming part of this specification, Figure 1 is a side view of a portion of a boom with a dipper suspended thereon and embodying my invention, Fig. 2 is a sectional view illustrating the preferred manner of supporting the dipper on the boom and the arrangement of the cleaning device in the dipper, Fig. 3 is a transverse sectional view of the dipper.

In the drawing, 2 represents a boom of ordinary construction. I have not thought it necessary to illustrate the mast in connection with this bottom, as it is of ordinary construction and forms no part of my present invention.

3 is a bracket, rigidly secured to the outer portion of the boom and 4 is an excavating dipper that is mounted on a casing 5 pivotally connected to the lower end of the bracket 3. A sheave 6 is mounted in the end of the boom and a cable 7 passes over this sheave and is connected at 8 to the bucket and has the function of swinging the bucket from its loading to its dumping position.

9 is a bail, pivoted on the bucket, and 10 is a cable connected thereto which may be designated as the loading cable, being adapted to drag the bucket through the material in the excavation.

11 is a shaft journalized in bearings in the outer portion of the boom and having a pulley 12 mounted therein to receive a driving cable 13 by means of which the shaft 11 is

revolved. This shaft depends below the boom and has a fork 14 at its lower end. A stud 15 is mounted to rotate in a hub 16 on the casing 5 and has a tongue 17 formed thereon that is adapted to pass between the arms of the fork 14 when the bucket or dipper is swung to its dumping position. During the loading operation, the tongue passes out from between the arms of the fork, as indicated by dotted lines in Fig. 1, and the bucket may then be drawn through the material until it is filled.

The stud 15 projects through the head of the bucket and supports a scraper 18, U-shaped, substantially, in form, and fitting against the head and walls of the bucket and having edges preferably beveled, as indicated at 19, to scrape the inner surface of the bucket and prevent the clay or other tenacious material that may be gathered up from sticking to the walls of the bucket and interfering with the discharge of the load. It may not be necessary in all instances to operate this scraper and provision may be made for operating it only in case that the load sticks in the bucket. In handling sand the operation of the cleaning device might be eliminated, but in wet soil of a clay nature the material will nearly always stick to the walls of the bucket and provision may be made for operating the cable 13 with each discharge and thereby insuring the thorough cleaning out of the bucket each time that it is inverted to a dumping position. It will be noted that this scraper operates on the head or bottom of the bucket as well as on the walls thereof, and a thorough cleaning and scraping of the walls is thereby insured.

I claim as my invention:

1. The combination, with a boom, and an excavating bucket pivoted thereon, of a scraper mounted to revolve on the bottom of said bucket on the inside thereof and having means to sweep the inner surface of said bottom and the walls of said bucket, cables having running connections with said boom and with said bucket, and means mounted on said boom and operatively connected with said scraper for operating it to clean said bucket.

2. The combination, with a boom, of an excavating bucket pivoted thereon, a dumping cable connected to said bucket and having a running connection with said boom, a loading cable connected to said bucket, a

scraper device having arms to sweep the inner surface of the walls of said bucket, and means mounted on said boom for operating said scraper device.

5. 3. The combination, with an excavating bucket having an open and a closed end, of a scraper device centrally mounted on the closed end of said bucket and having arms for scraping the surface of said closed end

10 and the inner surface of the walls of said bucket, a boom whereon said bucket is pivoted, cables having running connections with said boom and with said bucket for loading and dumping said bucket, and operating means for said device mounted on said boom and connected with said device.

4. The combination, with a boom, of an excavating bucket pivoted thereon, a cleaning device mounted in said bucket and 20 means mounted on said boom and becoming operative to revolve said cleaning device when said bucket is swung to its dumping position and becoming disengaged from said cleaning device and inoperative when said bucket is swung to its loading position.

5. The combination, with a boom, of an excavating bucket pivoted thereon, a shaft mounted in said boom, means for revolving said shaft, loading and dumping cables 30 connected to said bucket, a scraper device mounted in said bucket, and means for temporarily coupling said scraper device and said shaft together when said bucket is swung to its dumping position, said scraping device becoming automatically uncoupled from said shaft when said bucket is swung to its loading position.

6. The combination, with a boom, of an excavating bucket pivoted thereon, loading

and dumping cables for said bucket, a revolving shaft journaled in said boom and having a forked end, a stud mounted in the head of said bucket and having a tongue to enter the fork of said shaft when said bucket is swung to its dumping position, 45 and a scraper mounted on said stud and adapted to clean the walls of said bucket.

7. The combination, with a boom and an excavating bucket, of a cleaning device, means becoming operative to actuate said 50 cleaning device when said bucket is moved to its dumping position and becoming disengaged from said cleaning device and temporarily inoperative when said bucket is moved to its loading position.

8. The combination, with an excavating bucket, of a scraper mounted to revolve therein and having means to clean the walls of said bucket, and means becoming temporarily inoperative when said bucket is 60 moved to its loading position for revolving said scraper within said bucket.

9. The combination, with a boom and an excavating bucket, of a revolving shaft, loading and dumping cables, a scraper device mounted to operate in said bucket, means for temporarily coupling said scraper device and said shaft together when said bucket is swung to its dumping position, 65 said scraping device becoming automatically uncoupled from said shaft when said bucket is swung to its loading position.

In witness whereof, I have hereunto set my hand this 7th day of June 1913.

EMIL A. ANDERSON.
